UNITED STATES PATENT OFFICE.

FRED THEODOR GERDES, OF ROCHESTER, INDIANA.

GRAIN-CAR DOOR.

1,274,159.

Specification of Letters Patent. Patented July 30, 1918.

Application filed December 12, 1917. Serial No. 206,804.

To all whom it may concern:

Be it known that FRED T. GERDES, a citizen of the United States, residing at Rochester, in the county of Fulton and State of Indiana, has invented certain new and useful Improvements in Grain-Car Doors, of which the following is a specification, reference being had to the accompanying drawings.

10 This invention relates to freight car doors, and particularly to means for mounting freight car doors so that they may slide longitudinally or be swung out with their lower edges away from the wall of the car.

15 The general object of this invention is to provide very simple, effective and easily operated means to this end which may be applied to all makes of cars, without change.

20 A further object is to provide a construction whereby the door proper may be forced inward against the jambs of the doorway against the pressure of grain or other material carried within the car.

25 A further object is to so construct the door that when the door is forced inward it will be locked against any longitudinal sliding movement.

30 A further object is to provide improved means for swingingly and slidably supporting the door and provide improved means for locking the lower edge of the door against any outward movement.

Other objects will appear in the course of the following description.

35 My invention is illustrated in the accompanying drawings, wherein:

Figure 1 is a front view of a portion of a freight car with my improved door thereon;

40 Fig. 2 is a vertical sectional view on the line 2—2 of Fig. 1, showing the door shifted outward showing in dotted lines the door swung outward;

Fig. 3 is an enlarged fragmentary section on the line 3—3 of Fig. 1;

45 Fig. 4 is an enlarged fragmentary vertical section on the line 4—4 of Fig. 1;

Fig. 5 is an enlarged vertical section through the upper rail on the line 5—5 of Fig. 1;

50 Fig. 6 is a like view to Fig. 5, but taken on the line 6—6 of Fig. 1; and

Fig. 7 is a perspective view of one of the slides 15 and its shanks.

55 Fig. 8 is a fragmentary perspective view of one pair of hangers and a portion of the

locking rail, the locking rail being shown partly in section.

In the accompanying drawing, 10 designates the wall of a freight car of any usual and suitable construction having the doorway 11. Mounted upon supporting brackets on the side wall of the car in a line above the door opening is a longitudinally extending split tube 12 to thereby provide a tube having a longitudinally extending slot 13 in its bottom. The front wall of this tube is notched as at 14 at a plurality of points. Sliding within the tube 12 are the sliding members 15 having shanks 16 which extend downward through the longitudinal slit 13. There are two of these slides 15. Attached to the shanks 16, of which there are two to each slide 15, are the depending angle irons 17 having outwardly projecting flanges 18. These flanges 18 do not extend to the lower ends of the angle irons, but the other flange of each angle iron is extended and bent to form a hook 19 there being a transverse head 19^a connecting said hooks and extending in a plane at right angles to the length of the hangers.

Rotatably mounted upon the side wall of the car below the door opening is a rail 20, this rail being rotatably mounted in brackets 21. This rail is arcuate in cross section so as to provide a slit 22 within which the hooks and head engage, as illustrated in Fig. 4, this slot having circumferential extensions 22^a. When the rail is turned in one direction, it will interlock with the head 19^a, as illustrated in Fig. 4 and lock the angle irons 17 to the rail. When, however, the rail is turned in a reverse direction so as to bring the slot toward the front, the rail will disengage from the head 19^a and allow the angle irons to be shifted outward. The rail may be turned by any suitable means and I have shown for this purpose a common handle 23, which is adapted to be engaged by a latch 24 and locked in a position to lock the angle irons 17 against movement.

The door 25 may be made of sheet steel or wood and may be made of any suitable construction, but preferably the door is provided at its upper end with an opening 26, normally closed by a door which provides means whereby grain may be loaded in a car. The door 25 is provided adjacent its upper and lower ends and inward of its side edges with racks 27, these racks having down-

wardly projecting teeth. Passing through the flanges of the angle irons 18 and rotatively mounted therein is a shaft 28 carrying toothed wheels 29, these toothed wheels 5 being disposed between the flanges of each pair of angle irons and these toothed wheels engage with the U-shaped racks 27 and act to support the door. By rotating the shafts 28, however, the door may be forced inward 10 with relation to the angle irons, that is, forced inward toward the jambs of the doorway or may be shifted outward with relation to the angle irons. I do not wish to be limited to any particular means for operating these gear wheels 29, but I have shown for this purpose, arms 30 extending from the shafts 28, these arms being connected by a rod 31 having a yoke 32 at its middle through which passes a lever 33 mounted 15 upon the car door. The rod 31 is formed of jointed sections so as to permit an easy movement of the rod and of the lever. When this lever is rotated in one direction to the position shown in Fig. 2, the door will 20 be shifted to an open position and when it is rotated in the opposite direction for its full stroke, as indicated in dotted lines in Fig. 2, the door is shifted toward the jambs. Preferably, locking means are provided for 25 the lever so as to hold it in a position where the door 25 is urged against the jambs. Any suitable locking device may be provided for this purpose.

With this construction, when it is desired 30 to hold the door closed, the locking rail 20 is rotated so as to engage the lower ends of the angle irons 17 and then the door is forced inward by shifting the lever 33 until the door is urged firmly against the 35 jambs. Under these circumstances, the door with its hangers formed by the angle iron 17 cannot be shifted longitudinally along the rails 12 and 20 and the door is held locked. Furthermore, the door cannot be 40 shifted outward with the hangers because the lower ends of the hangers are locked to the rails 20. Now when it is desired to unload the car, the first thing to do is to shift the lever 33 to draw the door 45 outward sufficiently to clear the jambs. Then if the car is loaded with grain it is best to unlock the locking rail 20 from its engagement with the hooks 19 and then the pressure of the grain will swing the door 50 outward at its lower edge, thus releasing a certain portion of the grain. When the hangers 17 are swung back again to a vertical position, they may be shifted along the rail 12, by engaging the lower ends of the 55 hangers with the rail, that is the angle irons may be engaged with the rail 20 interlocking the rail therewith and then the hangers and the door may be shifted laterally upon the rails 12 and 20. It will be seen that this 60 construction is very simple, relatively light 65

and that it may be applied to all forms of freight cars having a door opening in the side wall. While I have described this door with special reference to its use on freight cars, it will be understood that a like construction may be used for mounting doors in other situations. 70

Having described my invention, what I claim is:—

1. In a door construction, a wall having a 75 doorway, a rail disposed above the doorway, hangers slidably mounted upon the rail and swingingly mounted thereon for movement away from or toward the wall, a door carried by said hangers, and a locking rail extending longitudinally below the door opening and shiftable into or out of interlocking sliding engagement with the hangers. 80

2. In a door construction, a wall having a doorway, a rail disposed above the doorway, 85 hangers slidably mounted upon the rail and swingingly mounted thereon for movement away from or toward the wall, a door carried by said hangers, a locking rail extending longitudinally below the door 90 opening and shiftable into or out of interlocking sliding engagement with the hangers, and means for forcing the door toward or away from the hangers. 95

3. A door construction of the character 95 described including a wall having an opening, a longitudinally extending rail mounted upon the wall above the door opening, hangers having sliding engagement with the rail for longitudinal movement therealong 100 and having rotative engagement with the rail for movement in a vertical plane, a second rail disposed below the door opening, the hangers extending downward thereto and having detachable sliding engagement 105 therewith, a door disposed inside of said hangers, and means carried by the hangers for supporting the door and shifting the door toward or from the wall of the car. 110

4. A door construction including a wall 110 having a door opening, a longitudinally extending rail mounted above the door opening, hangers having sliding engagement with the rail and rotative engagement therewith and extending below the door opening, 115 a lower rotatably mounted rail disposed below the door opening, said lower rail being hollow and longitudinally slotted, the lower ends of said hangers being provided with hooks adapted to engage within said slot, 120 means for rotating the lower rail to engage it or disengage it from the lower ends of the hangers, and a door carried by said hangers. 125

5. A door construction including a wall 125 having a doorway, a hollow longitudinally slotted rail extending above the doorway, door supporting hangers having slides disposed within the hollow rail and having shanks extending through the slot of the rail 130

- and connecting with the hangers, the rail at predetermined points being upwardly slotted from said longitudinal slot to accommodate the shanks of the hangers and permit a rotative movement of the hangers in a vertical plane, means for locking the lower ends of the hangers against swinging movement in vertical planes, and a door carried upon the hangers.
- 10 6. A door construction including a wall having a doorway, a hollow longitudinally slotted rail extending above the doorway, door supporting hangers having slides disposed within the hollow rail and having shanks extending through the slot of the rail and connecting with the hangers, the rail at predetermined points being upwardly slotted from said longitudinal slot to accommodate the shanks of the hangers and permit a rotative movement of the hangers in a vertical plane, means for locking the lower ends of the hangers against swinging movement in vertical planes, a door carried upon the hangers, and means mounted on the hangers for shifting said door toward or from the wall.
7. A door construction including a wall having an opening, upper and lower rails, hangers slidably engaging said rails, upper and lower shafts extending through said hangers and having gear wheels thereon, a door having U-shaped members passing through the hangers and having rack teeth engaged by said gear wheels, and means mounted on the door for rotating said shafts to thereby shift the door inward or outward.
8. A door construction including a wall having an opening, a longitudinally extending rail mounted above the door, hangers mounted upon the rail and extending below the door opening, a lower longitudinally extending rail with which the hangers have sliding engagement, said hangers comprising two pairs of angle irons, the angle irons of each pair being spaced from each other
- 5 and arranged with certain of the flanges projecting outward, upper and lower shafts rotatably mounted in said flanges, gear wheels mounted on the shaft between the angle irons of each pair of angle irons, a door, U-shaped members mounted upon the face of the door and extending between the angle irons of each pair of angle irons and around said gear wheels, the U-shaped members being interiorly toothed to engage therewith, a lever mounted on the door, arms extending from the shafts, and means operatively connecting the lever to the arms to cause a rotation of the shaft upon the shifting of the lever.
- 15 9. In a door construction, a wall having a doorway, a rail disposed above the doorway, hangers slidably mounted upon the rail and swingingly mounted thereon for movement away from or toward the doorway, a door carried upon the hangers, means disposed below the doorway for engaging the door to hold it from outward swinging movement, said means being shiftable to a position to permit the outward swinging movement, and means for forcing the door toward or away from the hangers to thereby hold the door away from said wall or hold it against the wall respectively.
- 20 10. In a door construction a wall having a doorway, a rail disposed above the doorway, hangers slidably mounted upon the rail, a lower rail extending longitudinally below the door opening and with which said hangers engage, a door carried by the hangers, means for urging the door toward or away from the hangers, and means for disengaging the lower rail from its engagement with the hangers.
- 25 11. In a door construction a wall having a doorway, a rail disposed above the doorway, hangers slidably mounted upon the rail, a lower rail extending longitudinally below the door opening and with which said hangers engage, a door carried by the hangers, means for urging the door toward or away from the hangers, and means for disengaging the lower rail from its engagement with the hangers.
- 30 12. In a door construction a wall having a doorway, a rail disposed above the doorway, hangers slidably mounted upon the rail, a lower rail extending longitudinally below the door opening and with which said hangers engage, a door carried by the hangers, means for urging the door toward or away from the hangers, and means for disengaging the lower rail from its engagement with the hangers.
- 35 13. In a door construction a wall having a doorway, a rail disposed above the doorway, hangers slidably mounted upon the rail, a lower rail extending longitudinally below the door opening and with which said hangers engage, a door carried by the hangers, means for urging the door toward or away from the hangers, and means for disengaging the lower rail from its engagement with the hangers.
- 40 14. In a door construction a wall having a doorway, a rail disposed above the doorway, hangers slidably mounted upon the rail, a lower rail extending longitudinally below the door opening and with which said hangers engage, a door carried by the hangers, means for urging the door toward or away from the hangers, and means for disengaging the lower rail from its engagement with the hangers.
- 45 15. In a door construction a wall having a doorway, a rail disposed above the doorway, hangers slidably mounted upon the rail, a lower rail extending longitudinally below the door opening and with which said hangers engage, a door carried by the hangers, means for urging the door toward or away from the hangers, and means for disengaging the lower rail from its engagement with the hangers.
